Application June 28, 1949, Serial No. 101,739

31 Claims. (Cl. 197—63)

1

This invention relates to typewriting machines and more particularly to mechanisms for adjusting carriage arresting stops, such as margin stops, to desired positions by manipulations involving stop-shifting movement of the carriage, without the operator ever laying hands directly on such stops.

Stop setting mechanisms of this general species have been devised particularly for typewriting machines wherein the stops to be adjusted are located behind the paper supporting devices and are inconvenient for access.

In recent years, inventors have aimed to provide for more convenient adjustment of such inaccessibly located stops. In some structures devised, the stops are released and spring-moved toward an associated counterstop in response to an operation of a manipulative member provided on the carriage or in the keyboard of the machine. The procedure in connection with such devices calls for tedious and laborious manual movement of the carriage in the appropriate direction to bring the carriage to the exact position in which it is desired to have the stop engage the counterstop. At the proper moment in the procedure the stated manipulative member must be restored to secure the stop in the new position of adjustment. The manipulative procedures generally require movements of the operator's hands from and to the keyboard, are tedious, tiresome and confusing and an operator is often discouraged from making desirable margin stop adjustments, except when the reasons are absolutely compelling for doing it. Moreover, in this particular type of mechanism the procedure must be radically varied depending on whether a stop is required to be shifted outwardly or inwardly from the old position. This condition is apt to confuse the operator and in any event calls for considerable mental effort.

In other known structures, preparatory to effecting a margin stop adjustment, the carriage must first be hand-moved leftwardly or rightwardly, to bring the stop which is required to be adjusted against the counterstop. After such manual movement of the carriage is completed, and not before, a control must be actuated to release the stop for adjustment and to render it stationary with respect to the counterstop. Still more subsequently, the carriage is required to be moved by manual effort, in a cumbersome and time-consuming manner, to the position corresponding to where the stop is required to be stationed. Additionally, as part of the procedure, the margin stop releasing control must then be

2

restored to cause the locking of the stop in the newly established position.

In either of the above outlined species of structures, the stop adjusting operations become taxing to the operator in view of varying requirements of procedure, which involve hand movements from the keyboard, and particularly also in the face of carriage movements which must be imparted tediously by manual effort and at the proper time, and with much exercise of mental judgment.

According to prior mechanisms it is particularly not feasible to effect margin stop adjustments, reliably and speedily, by convenient and light manipulative action confined entirely to the keyboard of the machine or to the immediate proximity thereof.

With a view of eliminating the deficiencies of prior devices, it is an important object of the present invention to provide mechanism for efficiently effecting adjustments of stops by remote control, rapidly, through easy, non-fatiguing, simple manipulative action on the part of the operator, and without any sacrifice or impairment of conventional typewriter functions.

It is a further object to accomplish the foregoing object by conveniently manageable manipulative means that are in the keyboard of the machine or immediately adjacent thereto, and which provide for high speed adjustment of the stops in either direction followed, if necessary, by precise incremental adjustment to the exact position desired.

It is another object of the invention to provide for efficient, remote-control stop adjustment by provision of power agencies for doing all heavy work, and particularly also by provision of power-means to step-wise move the carriage in either direction to the end of effecting all margin stop adjustments expeditiously with precision and with least effort and possibility for mental confusion.

It is also an object of the invention to provide an efficiently manipulative margin stop adjusting device which has no delicate spring means to effect movements of the stops against a counterstop.

It is moreover an object to provide a device of the type stated, in which a margin stop unlocking or releasing key may be operated prematurely, before the positioning of a margin stop against the counterstop, provision being made to delay the stop releasing action of the device until such time as the margin stop is in a relation of engagement with the counterstop, thus avoiding a

serious objection to prior devices which require that the margin stop unlocking mechanism be operated at a special point in a sequence to prevent loss of control of the margin stop and a consequent failure in the setting operation.

It is also an object of the invention to provide a device of the nature stated, which will unlock a margin stop from its support for adjustment only following the bringing of a margin stop against the counterstop, and which device concomitantly to unlocking a stop will securely hold it in a fixed relation to the counterstop.

A still further object is to provide a reliably operative, rugged stop releasing mechanism which is incapable of effective actuation until or unless a stop to be adjusted is first brought into appropriate relation with the counterstop.

A general object is also to provide a mechanism of the stated purpose, which is rugged in structure, accurate in operation, and not subject to stall or tie up the machine due to improper manipulation.

In conjunction with a line-end locking mechanism for typing instrumentalities and a power-operated carriage stepping mechanism, it is an object to provide means whereby a special manipulative control for causing repeated action of said carriage stepping mechanism, when operated, renders the line-end locking mechanism incapacitated in regards to the said power-operated stepping mechanism.

Other objects of the invention will become evident in the light of the detailed description of the preferred embodiment of the invention which follows.

Now referring to the drawings:

Figure 1 is a skeletonized, sectional side view of a typewriter embodying a carriage, as viewed from the right side of the machine, some of the mechanism being shown whereby adjustment of margin stops is advantageously effectable.

Figure 2 shows a device to effect repeated step movements of the carriage to the end of effecting adjustments of the margin stop leftwardly on the carriage.

Figure 3 is a sectional front elevation of the rear portion of the typewriter, and including some of the mechanism for effecting margin stop adjustments.

Figure 4 is an enlarged front elevation of a margin stop also seen in Figure 3.

Figure 5 is a fragmentary perspective view showing mainly a portion of the mechanism for unlocking the margin stops for adjustment.

Figure 6 is a perspective view illustrating a margin stop unlocked from its support for adjustment, and having been rendered concomitantly stationary with respect to a counterstop.

Figure 7 is a diagrammatic plan view of a typewriter keyboard, embodying manipulative means to effect efficiently adjustments of the margin stops.

Figure 8 is a fragmentary front elevation of a margin stop unlocking device in a state of readiness for resultful action on a margin stop just as soon as such stop moves a little more leftwardly.

Figure 9 is a skeleton perspective view of a margin stop controlled line-end locking mechanism for the typing instrumentalities and a carriage spacing mechanism, the latter including a letter-feed actuator, having associated therewith key-means to call it into operation independently of the locking mechanism.

Finally, Figure 10 is a plan view of part of a

mechanism used for leftward adjustment of the margin stops.

Referring now more particularly to the sectional side view of Figure 1, a carriage 15 includes two spaced end plates 19 connected by a rail 16. Said rail is guided to travel linearly between two parallel trackways 18 by use of anti-friction elements 17, said trackways 18 being carried upon spaced side walls 20 of the main framework of the machine. The carriage includes a usual platen roll 21 for support of work sheets. A usual complement of types are adapted to strike against the front side of the platen at a common printing point, as indicated by a type bar 22 shown in dot and dash lines. The carriage is urged constantly in leftward, letter-feed direction under the power of a spring motor 23 having a draw band connection 24 with the carriage, but a usual letter-feed escapement 25 associated with an escapement wheel 26 is normally in control over the carriage to hold it against the urge of said spring motor 23. A vertically disposed shaft 27 operatively connects said escapement wheel with a pinion 28 which is in mesh with a letter-feed rack 30 supported on and partaking of the movements of the carriage 15. Said escapement 25 comprises a rocker frame 33 carrying a holding dog 31 which is normally in carriage holding engagement with one of the teeth of the escapement wheel 26, but which in a usual manner permits free travel of the carriage rightwardly in carriage return direction. The rocker frame 33 comprises also a stepping dog 34, and is pivoted on an axis 29 which extends transversely of the machine. At each typing operation and at each word spacing operation the escapement rocker 33 receives a momentary downward rocking motion, swinging the holding dog 31 clear of the teeth of the escapement wheel 26 and temporarily swinging the stepping dog 34 between two teeth of the escapement wheel to permit the latter to turn somewhat less than a letter-feeding step. Responsive to the return motion of the rocker 33, which follows immediately, the escapement wheel will complete its letter-feeding step, the end result being that the carriage will have lettered one space.

The operating mechanism for the type bars 22 may correspond to that shown in the patent to Yaeger, No. 2,254,764, dated September 2, 1941, namely type keys 36 in a keyboard 39, see Figure 7, by the means disclosed in the stated patent, are adapted to engage selectively type bar actuators 37 with a constantly rotating toothed power member 38, said means including a hook member 40 for engaging each actuator, see Figure 9. Each operation of a type bar 22 results in a letter-feeding step of the carriage by an actuation of the escapement 25, in a conventional manner.

The normal limits of carriage travel are adjustably established by a left and a right margin stop, respectively numbered 44 and 45, which stops cooperate with a counterstop 46. In the embodiment of the invention shown, the margin stops 44 and 45 are supported for adjustment in parallel to the carriage, on a toothed rack bar 47 which is carried fast on the opposite end plates 48 of the carriage 15. As best seen in Figures 3, 4, 5 and 6, the individual margin stops comprise each a block or body having a rectangular perforation 51 extending lengthwise of the carriage for slidable accommodation of the stop on the rack bar 47. Each of the stops 44, 45 is normally locked lengthwise on the rack bar by means of a lock slide 52 accommodated in the stop for downward movement in a vertical slot

53 which is closed at the front. Said lock slides 52 are confined for downward movement between the closed front side of the slot 53 and the front side of the bar 47, and each has a rearwardly reaching nose 54 for meshing upwardly in the tooth notches 55 of the rack 47. Compression springs 56 underlying horizontal flanges of the lock slides 52 urge the latter constantly upwardly for stop locking engagement of the nose 54 with the rack 47. The lower ends of the springs 56 are accommodated in socket holes provided in the stop bodies, as shown. It will thus be seen that adjustment of either of the margin stops 44, 45 entails movement of the appropriate lock slide 52 downwardly. Such stop-releasing movements of the lock slides 52 are effected under keyboard control in a manner which will be brought out later.

The counterstop 46, see Figure 9, comprises the upper end of an upright arm 60 which is disposed approximately mid-way between the side walls 20 of the typewriter, the counterstop 46 protruding upwardly through a rectangular perforation 61 in a top plate 62 of a small mechanism supporting housing 63. The counterstop arm 60 has at its lower end a vertical slot 64, and extending through this slot for mounting the arm is a headed stud 65, the latter projecting rigidly from the rear of a cross member 66 of the framework. A spring 67 urges normally the counterstop arm 60 upwardly to the limit provided by the lower end of the slot 64, and another spring 68 has a rightward action on the arm 60 for the counterstop end 46 to abut normally the right side of the perforation 61. The left margin stop 44 is normally at the left of the counterstop 46, whereas the right margin stop is normally at the right thereof, the margin stops having stop faces 70 oppositely facing toward the counterstop 46.

In the course of typing a line, the carriage travels leftwardly, and if the right margin stop 45 travels sufficiently far it will engage the counterstop 46 to displace it leftwardly a distance substantially equivalent to a letter-feed space. This displacement of the counterstop, as will be brought out later, serves to lock the typing mechanism, as well as a word spacing mechanism against operation.

As has been stated hereinabove, it is an important object of the invention to adjust the margin stops selectively by easy manipulative action confined entirely to the keyboard. The stop adjusting operation involves successive operative stages, comprising, power movement of the carriage in appropriate direction to bring first the stop to be adjusted against the counterstop 46, unlocking of the appropriate margin stop and the rendering of such unlocked stop stationary with respect to the frame, power movement of the carriage step-wise, rapidly, either to the right or to the left while the unlocked stop remains stationary with respect to the counterstop, thereby to effect a stop adjustment, and finally a restoration of the machine to a normal state, wherein the newly adjusted margin stop is locked in its new position on its support.

If adjustment of the right margin stop 45 is required, the operator depresses a tabulator key 71 to cause propulsion of the carriage 15 leftwardly under power of the carriage feed motor 23, thereby to bring the margin stop 45 into line-end limiting engagement with the counterstop 46. If the left margin stop 44 is to be adjusted, the operator depresses either one of two carriage

75 Figure 1, by engagement with the right side of

return keys 72, responsive to which there will ensue a power-driven movement of the carriage 15 to the limit determined by the engagement of the margin stop 44 with the counterstop 46.

5 The tabulating mechanism for bringing the stop 45 against the counterstop may be substantially as disclosed in the patent to Helmond, No. 2,303,878, dated December 1, 1942, in which a tabulator key like the one herein numbered 71 in Figure 7, upon depression causes an upward power actuation of a link 73 seen in Figure 1. Said upward actuation of the link 73 is effected by an actuator similar to the type-action actuator 37 seen in Figure 9, and the said link in turn 10 rocks a lever 74 about a stationary fulcrum rod 75, and projects a tabulator reed upwardly. When so projected, the reed 76 may be in carriage intercepting range with any tabulator stop 77 carried on a rack 78 and set downwardly thereon to a potentially effective position. The forward end of the lever 74 has a pin-and-fork connection with a lever 80 which is pivoted at 81 and has a down-reaching arm 82 for displacement of the holding dog 31 of the escapement clear of the 15 escapement wheel 26. Thus whenever the tabulator reed 76 is projected in response to operation of the key 71, the holding dog 31 is thrown concomitantly free of the escapement wheel, and the carriage resultingly will be power driven in leftward direction by the spring motor 23.

The tabulator reed 76 is normally in the lower position seen in Figure 1, and such position is established under the tension of a spring 83 which pulls the reed downwardly, and the upper end 20 rightwardly, the upper end of the reed being accommodated in a rectangular hole 79 with capacity for some rightward displacement, and motion of the reed in downward direction being limited by a rod 84 wherewith the upper end of 25 a slot in the reed engages. Said tabulator reed 76 has a rightwardly extending shoulder 85 which under the rightward urge of the spring 83 latches or catches over a small shelf 86 as the reed reaches projected position. When tabulations 30 are effected to station the carriage in tabulated positions intermediate the limits of carriage travel established by the margin stops 44, 45, the reed 76 projected in response to the operation of the tabulator key 71 is encountered by the downwardly set tabulator stop 77 in range thereof to 35 the right. The tabulating run is terminated when such tabulator stop displaces the reed 76 leftwardly to the limit permitted by the hole 79. When this happens the reed shoulder 85 slips off the shelf 86, and enables the spring 83 to restore 40 the tabulator reed 76, the holding dog 31 of the escapement consequently regaining control over the carriage 15 to hold the latter in the newly attained position.

45 When the right margin stop 45 is to be brought into line-end limiting engagement with the counterstop 46, as the first step in an adjusting operation for such stop, the tabulator key 71 may have to be operated several times to cause the carriage to move sufficiently far. Moreover, there may be no tabulator stop 77 set to cause the restoration of the reed 76 when the margin establishing 50 engagement takes place between the stop 45 and the counterstop. To assure restoration of the reed 76, the leftward displacement of the counterstop arm 60 in the line-end limiting engagement is utilized to cause restoration of the reed 76. Specifically, a pin 87 projecting rearwardly 55 from and fast on the counterstop arm 60, see Figure 1, by engagement with the right side of

the tabulator reed 76 will effect a leftward displacement of the latter to free the shoulder 85 from the shelf 86, and thereby will cause the restoration of the tabulator reed out of range of the tabulator stop 77. It follows thus that the reed 76 will always restore automatically when the margin stop 45 assumes line-end limiting engagement with the counterstop 46. The carriage is thus left unobstructed by the tabulating reed 76 when subsequently the carriage is moved to effect margin stop adjustment. Obviously, also, the control of the escapement 25 over the escapement wheel is restored automatically at the end of the stated tabulation.

If it is the left margin stop 44 that is required to be adjusted, then as a first step in the adjusting procedure the carriage is preferably power-moved rightwardly to bring such stop 44 into movement-limiting engagement with the counterstop 46. Such power movement of the carriage is effected under control of either one of the aforesaid carriage return keys 72, and the mechanism which is responsive to such keys may be substantially that disclosed in the patent to Helmond, No. 2,262,676, dated November 11, 1941, and will now be described briefly in particular reference with Figure 3.

Carriage return motion is impartable to the carriage through a flexible strap 91 extending from a strap-winding drum 92 to a part, not shown, of a line-spacing mechanism on the carriage 45. The strap 91 extends from the drum 92 over several guiding elements, one of which is shown at 93. The drum 92 is normally rotatively free on a shaft 94 and has associated therewith a very lightly active spring motor 95 to turn it and take up the slack in the strap 91. Also turnably free on the shaft 94 is a clutch element 96 which has a splined connection, not shown, with the pulley 92. This permits the element 96 to be moved axially on the shaft, into clutched association with a gear 97 that is fast on the shaft 94, the said element 96 and the gear 97 having clutch teeth 98 normally separated from each other. A pinion shaft 103, constantly driven by an electric motor, not shown, drives the gear 97, but the clutch embodying the clutch teeth 98 being normally open, the strap 91 exerts normally no carriage returning pull on the carriage. The clutch element 96 is normally held in open clutch position by a latch mechanism comprising a latch 104, see Figure 3. Said latch 104 is pivotally supported at 105 on the right side plate 20 of the machine and a shoulder thereof normally overlies the right end of a lever 107 which is pivoted at 108 on the housing 63, and which has a link connection 110 with an arm 111 that is unitarily rockable with a shifter 112 for the clutch element 96. A spring 113 constantly tends to swing the arm 111 clockwise to close the clutch. When the latch 104 is released by operation of one of the carriage return keys 72, the lever 107 is free to move clockwise, resulting in closure of the clutch under the tension of the spring 113. The drum 92 is thus power-operated to wind the strap 91 and to draw the typewriter carriage rightwardly.

During the clutch closing movement of the lever 107, an upright arm 114 thereof swings leftwardly, and through a link 115 having a pin 116 abutting the right side of the counterstop arm 66, swings the latter leftwardly a small distance within the perforation 61 of the housing top plate. In the instituted carriage return, the carriage return limiting margin stop 44 finally

engages the counterstop 46, moving it to the right end of the opening 61. Resultingly, through the pin 116 and the link 115, the lever 107 will be restored clockwise to open clutch position, to the control of the latch mechanism comprising the latch 104.

After the clutch has opened and the momentum of the carriage has died, the carriage drops back a small distance in letter-feed direction, 10 such drop-back being facilitated by a back-lash of the escapement wheel 25 against the dog 34. The drop-back of the carriage follows any return operation and leaves the counterstop always free to move to clutch closing position, for example, 15 to activate the carriage return mechanism for effecting a line spacing operation, or to shift the margin stop 44 to extreme leftward position on the carriage, in a manner which will be noted later.

From the above it will be seen that mere operation of a carriage return key 72 will bring the margin stop 44 very nearly against the counterstop 46. Such operation may constitute the first step in the procedure for adjusting the stop 44.

The second step in the margin stop adjusting procedure entails the unlocking of the stop which in the first step of the adjusting procedure is brought against the counterstop 46. It further entails temporary coupling of the unlocked stop in a stationary relationship with the counterstop 46. In other words, control of the margin stop to be adjusted is transferred to holding control by the frame, thereby to render the margin stop adjustable by movement thereafter imparted to the carriage, such movement constituting the third step in the stop adjusting procedure.

The stated transfer of control of the individual margin stop 44 or 45 is effected by a frame-supported unlocking element 122 which is capable of downward movement and has a shelf 123 to descend down on and depress the margin stop lock slide 52 to the position seen in Figure 6, wherein the slide nose 54 is clear of the rack 47.

A stop unlocking key 124 is provided in the keyboard 39, see Figure 7, and, by means to be described, is capable of operating the unlocking element 122. However, as will be seen later, operation of the key 124 has resultful effect on the unlocking element 122 only if one of the margin stops 44 or 45 is brought into margin-gaging relation with the counterstop 46. Thus operating pressure may be exerted on said key 124 prematurely, but downward operation of the releaser 122 will be resultant only when one of the margin stops is in a relation of engagement with the counterstop 46, or following establishment of such a relation.

Referring to Figure 1, the key 124 comprises the forward end of a lever 125 which is pivoted on a wire 126 and has an upreaching arm 127. A pull link 128 extends rearwardly from said arm 127 for articulation to a bell crank 130, the latter fully seen in Figure 5. Said bell crank 130 has pivotal support at 131 on an upright ear 132 of a stationary bracket 133. A rearwardly extending arm 134 of the bell crank 130 underlies a leftwardly extending lever 135 having pivotal support at 136 on an upright web 137 of the bracket 133. The latter is rigidly secured by screws upon the crossbar 56 of the framework of the machine. The left end of the lever 135 overlies a pin 139 on a vertically guided element 138, such element for guidance at its lower end upon the headed stud 65 being slotted as at 140. At the upper end the element 138 has a slot 141 through

which the rod 75 extends, said element being upwardly urged by a spring 142, and the lower end of the slot by engagement with the rod establishing the normal position of the element 138. The rod 75 carries for the element 138, at each lateral side thereof, a confining element, not shown. The releaser 122 comprises a two-part structure including an upper part 143 adjustably joined to a lower part 144 by screws 145. The lower part 144 of the releaser 122 has a vertical slot 146, and a headed pin 147 projecting from an ear 150 of the element 138 has connection with the part 144 in said slot. A spring 151 stretched between the left end of the pin 147 and a portion of the releaser 122 provides a yieldable connection therebetween, the purpose of which will become evident as the description proceeds.

The upper part of the unlocking element 122 passes through a rectangular hole in a slide 152, the latter of which is carried for limited forward movement on the underside of the top plate 62. For guiding the slide 152, two shouldered studs 153 and 154 reach upwardly through slots 155 provided in the slide, and are fast on the underside of the plate 62. A spring 156, attached to an ear of the slide 152, urges the latter rearwardly to normal position seen in Figures 1 and 5, wherein the pin 154 is engaged by the front end of its slot 155. In such position of the slide 152, the unlocking element 122 is blocked against downward movement by a protuberance 157 on the top plate 62, said protuberance underlying a shoulder provided by the upper side of a hole 160 in the element 122. The protuberance 157 and the shoulder may be considered to constitute a primary blocking means for the element 122, which means is effective at all times except when one or the other margin stop 44, 45 is at or close to the counterstop 46. The primary blocking means is automatically released when either margin stop 44, 45 approaches margin limiting engagement with the counter stop 46. Specifically, the margin stop 44 carries a cam element 161 at the front side thereof, which, when such margin stop approaches margin limiting engagement with the counterstop 46, is effective to cam the element 122 forwardly, about the pin 147, by camming engagement with a cam tappet 162 on the rear side of the releaser. The element 122 has at a higher level another cam tappet 163 which is engageable by a cam element 164 on the margin stop 45 to the same stated end. It will thus be seen that the primary blocking means constituted by the protuberance 157 and related shoulder is rendered ineffective when either of the margin stops 44, 45 nears the limit of carriage travel established thereby. The element 122 is flanked against lateral thrusts by two upright members 165 reaching from the plate 62.

A secondary or supplementary blocking means blocks downward operation of the element 122 when either margin stop rides into the neighborhood of the counterstop 46, but is automatically incapacitated as either of the margin stops reaches substantially exact margin-gaging position against the counterstop 46. Such secondary blocking means comprises on each one of the stops 44, 45 a member 165 which is slidably carried for downward displacement in a groove 166 of the respective stop block. A plate 167 facing the front side of the stop block, retains the slide member. The plates 167 have ears 168 flanking the opposite sides of the stop blocks, and screws 171 at said ears secure said plates to the blocks. The sliding members 165 have each a rearwardly

reaching lip 172 overlying a compression spring 173 reaching upwardly from a socket hole in the stop block. Urged by said springs 173, each slide member 165 occupies normally an upper position wherein a stop shoulder 174 thereof abuts a face 175 on the underside of the margin stop. When either of the margin stops 44, 45 nears the counterstop 46, the upper end of the slide member 165 of such stop will ride closely underneath the releaser shelf 123, while the lower end will ride closely over the housing top plate 62, the space between the normal position of the shelf 123 and the top plate 62 of the housing being slightly greater than the length of the slide member 165.

15 Toward conclusion of the leftward displacement of the counterstop 46 by the line-end margin stop 45, the lower end of the slide member 165 thereof arrives opposite a notch or interruption 176 in the plate 62, and the slide member consequently 20 is then free for depression by the stop unlocking element 122. Similarly, when the carriage return limiting margin stop 44 is arriving at return limiting position, the slide member 165 thereof arrives opposite a notch or interruption 177 in the 25 plate 62 and is then free for depression by the element 122. Inasmuch as said unlocking element 122 is always cammed forwardly just before either margin stop 44 or 45 arrives at margin limiting position, either margin stop when in limiting position against the counterstop is capable 30 of being unlocked by the element 122.

The margin stop 44 or 45 to be adjusted, having been brought to margin determining position against the counterstop 46, the operator operates 35 the margin stop unlocking key 124, and resulting the shelf 123 will descend down on the slide member 165 and on the lock slide 52, causing the former to enter the related notch 176 or 177 and causing the latter to release the stop from the supporting rack 47. It will be observed that the 40 effected engagement of the slide member 165 in the related notch 176 or 177 will localize the margin stop with reference to the machine frame and the counterstop, and also that the lock slide 52, being a little shorter at the top, will release the 45 margin stop only after the slide member 165 has entered the notch 176 or 177. In other words, downward movement of the releaser 122 transfers control of the margin from the carriage to the frame reliably in the exact relation to the counterstop.

Under sustained depression of the key 124, and thus with control of the margin stop transferred to the frame, the third step in the margin stop 50 adjusting procedure is taken which involves the impartation of small incremental power-movements to the carriage, leftwardly or rightwardly, to effect the actual margin stop adjustment. The incremental movements of the carriage 15 relatively to the localized margin stop are effected 55 under control of two stepping keys in the said keyboard 39, one key being numbered 180 and when depressed being effective to cause repeated incremental power-movements of the carriage leftwardly to effect rightward repositioning of the stop on the carriage, and another key being numbered 181 and when depressed being effective to cause repeated incremental power-movements of the carriage rightwardly and thereby 60 effect leftward relocation of the stop on the carriage.

The means which is responsive to said key 180 to effect step-wise adjustment of a margin stop rightwardly will now be described. The key 65 180 is on a key lever 182 which has pivotal sup-

port on a pivot wire 183 and which is urged upwardly to the normal position seen in Figure 1 by a spring 184. Engagement of the actuator 186 is effected responsive to operation of the key 180, through a cam face 178 on an upright element 185 of the lever 182, which cam face by action on a lug 179 of the actuator displaces the latter downwardly. Said actuator has a snatch pawl 187 pivoted thereon for some limited movement, and normally clear of the power member 38. A pendant arm, pivoted on an axis 190, supports the front end of the actuator movably in forward direction. A link 191 connects the rear end of the actuator 186 with an upright arm 192 of a pivoted structure comprising also an arm 193 having camming association with a roll 194 carried on the escapement rocker 33. Said pivoted structure includes further a connecting rock shaft 195 for the arms, pivotally supported on the framework of the machine and including also a downreaching arm 196 whereto there is connected a spring 197 which biases the pivoted structure 192, 193, 195 to return to the normal position seen in Figure 1, wherein the escapement rocker 33 under the tension of a spring indicated at 203 is in carriage holding position. A return spring 198 for the actuator 186 is arranged to bias the same upwardly against a stationary bar 200, and rearwardly for the pendant arm 188 to abut at 201. When the stop release key 180 is operated, the actuator 186 is driven forwardly in consequence of the connection effected between the snatch pawl 187 and the power member 38, and the movement is transmitted to the arm 193 which operates the escapement rocker 33 by camming action on the roller 194. Consequently, the escapement rocker 33 swings the dog 34 into mesh with the escapement wheel 26 and withdraws the dog 31. Subsequently, the actuator 186 is divorced automatically from the power member 38 by engagement of one of the teeth of the latter with a lug 202. Consequential to the return of the actuator, the escapement rocker moves toward normal position under the tension of the spring 203. If at this time the key 180 is still held depressed, there will be effected a re-engagement of the actuator 186 with the power member 38 by reason of the lug 179 riding downwardly and rearwardly along the cam face 178 of the upright member 185. Thus another power operation of the escapement will ensue, and further escapement operations will ensue until the key 180 is released, and the cam face 178 is consequently out of the path of the returning actuator lug 179. Margin stop adjustment rightwardly on the carriage to any position may thus be effected under control of the key 180, in rapid successive steps or increments by easy manipulative action of the key 180.

To aid the spring 198 to effect the return of the actuator 186, there is provided a lever 204 which normally bears on the pendant arm 188 under the tension of a spring 205. This lever 204, by reason of its momentum attained leaves the arm 188 when the actuator 186 becomes disconnected. Resultingly, the first part of the return stroke of the actuator 186 is effected solely under power of the spring 198. Just about the time when the lug 179 in its return nears the cam face 178, the lever 204 catches up with the returning pendant arm 188, and will exert a force thereon to assure reliable downward camming action of the lug 179 by the cam 178.

The machine embodies a conventional space bar 210, which through connections, not shown, 75

and including a key-less lever to the left of the lever 182, is adapted to operate a hook member 211 down on said lug 179 to engage the actuator 186. Such operation of the hook member 211 will result in a single operation of the actuator 186, even though the key 210 may be held depressed. This is because the lug 179 of the returning actuator 186 will on its return contact the hook member above the hook shoulder.

The upright member 185 is adjustably supported on the lever 182 to correlate the cam face 178 properly with the lug 179. To the stated end the upright member 185 is slidably supported in vertical direction upon the key lever 182 by means including a pin and slot connection 212, and a strong spring 213, arranged between the member 185 and the key lever 182, maintains the latter in engagement with an adjustable eccentric 214 on the key lever. In operation the member 185 is unitary with the lever 182.

The aforesaid key 181 and mechanism controlled thereby for effecting leftward adjustment of either margin stop incrementally by step-wise power movement of the carriage is illustrated in Figures 2 and 10. The key 181 is part of a lever 221 which is pivoted at 222 and is biased by a spring 223 to the normal position seen in Figure 2. A cam element 224, turnably carried on a reduced portion 225 of the toothed power member 38 near the left side plate of the machine, supports pivotally, as at 226, a clutch pawl 227. Said pawl is urged to swing into engagement with a toothed wheel 228 by a spring 229, the toothed wheel being fast on the reduced shaft portion 225. A dog 231, pivotally supported at 232, is normally in engagement with a shoulder of the pawl 227 for holding the latter clear of the wheel 228. Said dog is controlled by the key lever 221 through a pin-and-fork connection therewith at 233. The cam element 224 is adapted to operate a bail structure comprising an arm 234 closely to the left side wall 28 of the machine, an arm 235 near the middle of the machine, and a rock shaft 236 connecting the two arms rigidly. A follower roller 239 on the arm 234 contacts the cam element 224, and a pawl 237 connected to the arm 235 has its front end normally cammed clear of the escapement wheel 26 by a cam face 238 on the pawl contacting a stationary guide stud 240, see Figure 10. The shaft 236 has pivotal support at its right end in a frame boss 241, whereas the left end pivots normally in the lower end of a slot 242 due to a strong spring 243 having anchorage on the frame and being hooked to the shaft 236. There will be idle displacement of the left end of the shaft upwardly in the slot 242 whenever the pawl 237 is unable to turn the escapement wheel 26 due to the carriage having reached limit position. The roller 239 follows the cam element 224 under the tension of a spring 244 attached to the arm 234. A drop 245 on the cam, in conjunction with the roller 239, insures against backward rotation of the cam element following the throw-off of the clutch pawl 227. It will be seen that operation of the key 181 swings the dog 231 free of the pawl 227, causing the latter to engage the toothed wheel 228 under influence of the spring 229. Inasmuch as the toothed wheel 228 is constantly turning in the direction of the arrow, it follows that the cam element 224 then turns with the power member 38 so long as the key 181 remains depressed, and will complete a started turn after the release of the key, the dog 231, inter-

cepting then the clutch pawl 227 and swinging it free of the teeth of the wheel 228. The cam 224 power rotating under control of the key 181 causes repeated rocking movements of the structure 234, 235, 236 resulting in reciprocations of the pawl 237 which turn the escapement wheel 26 step-wise to step-wise move the carriage in rightward direction. Such step-wise movement effected after a margin stop has been unlocked and rendered stationary with respect to the frame, results in leftward step-wise adjustment of such stop.

It is conventional practice to provide means whereby responsive to the carriage riding to a line-end position, further typing and word spacing operations are automatically suppressed. Typing operations in the present machine are suppressed at line ends in the same manner as disclosed in the patent to Yaeger, No. 2,362,229, dated November 7, 1944. Namely, a toothed bar 248 slidably carried upon a cross bar 250, as at 251, for a short rightward movement from the position seen in Figure 9. Normally the rear ends of the type action actuators 37 overlie notches between teeth 252 of the bar, and such actuators are thus freely connectable to the power member 38 for power operation. However, when the line-end margin stop 45 displaces the counterstop 46 leftwardly, the teeth 251 come to lie underneath the actuators 37, rendering them incapable of connection to the power member 38, and thus incapable of operation. The rightward movement of the toothed bar 248 results when the counterstop arm 60 is displaced leftwardly by the stop 45 and displaces an arm 254 pivoted upon the framework of the machine on a stud 255 and connected through a spring 256 to a lever 257, the latter also pivoted at 255 and having a pin-and-fork connection 253 with the bar 248. A rearwardly extending arm 258 of the lever 257 provides for reliable return movement of the bar 248 whenever the counterstop is free to assume normal, rightward position under the power of the spring 68.

According to the invention the leftward displacement of the counterstop 46 blocks the space actuator 186 against connection with the power member 38 by the key 210. Nevertheless such space actuator 186 is readily connectable to the power member under control of the repeat stepping key 180. To accomplish this, the toothed bar 248 carries pivotally thereon, at 260, a lever 261 which includes an upright ear 262. A spring 263 urges said lever 261 normally against a stop pin 259 on the bar, and in this position of said lever the ear 262 is slightly to the left of the link 191 reaching rearwardly from the actuator 186. When the margin stop 45 operates the counterstop 46, the lever 261 will move rightwardly with the slide, and the ear 262 will become positioned underneath the link 191, to block the link 191 against downward motion necessary to connect the actuator 186 to the power member 38. Carriage spacing operation under control of the regular space key 210 is then prevented so long as the counterstop 46 remains leftwardly displaced.

For margin stop adjustment it is required to step-move the carriage while the margin stop 45 is in line-end locking position, and accordingly the stepping key 180, when operated is effective to move first the blocking ear from under the link 191. To this desired end the key lever 182 has an arm 264 reaching upwardly to the rear of an arm 265 of the lever 261, to swing the

latter clockwise for leftward displacement of the ear 262 from under the link 191. The arrangement is such that initial movement of the key lever 182 releases first the blocking condition established by the ear 262 and that during further movement of said key lever the cam face 178 will act on the actuator lug 179 to lower the actuator 186 for power operation. It will be noted that, although as stated the stepping key 180 is operable for effecting margin stop adjustment, the type actuators 37 remain blocked in idle position by the teeth 252 until, following the conclusion of the margin stop adjustment, the margin stop is moved rightwardly by the carriage, away from the counterstop 46, as by operation of one of the carriage return keys 72.

To move the carriage beyond either of the line limits defined by the said stops 44 and 45, the machine includes a usual margin release key 266 on a lever 267, see Figures 5 and 7. The lever 267 is adapted to operate a transverse lever 268, the left end of which is seen in Figure 9 and is adapted to lower the counterstop arm 60 including its stop end 46 below the margin stops, 25 the lock bar 248 in any event assuming then ineffective position.

The manipulative procedure for adjusting either of the margin stops 44 or 45, will now be described briefly in connection with the manipulative controls which have been described hereinabove.

If the left margin stop 44 is to be adjusted, the operator fingers a carriage return key 72, which brings such margin stop as a unitary part 35 of the carriage against the counterstop 46. This is the first step in the procedure and may be omitted if the operator knows that the appropriate margin stop is already against the counterstop. In case of doubt the operator touches the return key 72 to make certain that the stop will be against the counterstop.

Thereupon, as the second step in the procedure, the stop unlocking key 124 is operated, resulting in the operation of the element 122 downwardly 45 to unlock the stop 44 from the carriage and concomitantly to lock it to the frame, stationary with respect to the counterstop 46.

The third step in the procedure consists of operating the appropriate stepping key 180 or 181 for effecting repeatedly power stepping movements of the carriage, thereby to cause adjustment of the stop 44 rightwardly or leftwardly on the carriage, as may be required, the release key 124 being meanwhile still held depressed.

55 By appropriately timing the release of the operated stepping key, the desired position of the margin stop 44 on the carriage is obtained. The release of the key 180 or 181, coupled with a release of the stop unlocking key 124 may be regarded as the fourth or final step in the margin stop adjusting procedure. As a result of this fourth step the margin stop 44 is appropriately locked to the carriage rack 47 by the restoration of the lock slide 52, and freed from control by the frame by the restoration of the slide member 165.

The procedure for adjusting the right margin stop 45 is similar, but to bring such stop against the counterstop, the tabulator key 71 is operated 70 instead of the carriage return key. The tabulator key need not be operated if the stop 45 is in line-limiting position against the counterstop 46. As in the case of adjusting the margin stop 44, the stop unlocking key 124 is then operated 75 to transfer control of the stop 45 from the car-

riage to the frame. This is followed by the third step in the procedure, which consists of operating the appropriate stepping key 180 or 181 for a period until power adjustment of the unlocked margin stop 45 leftwardly or rightwardly on the carriage to the appropriate position has been effected by carriage movement. Finally the operated key 180 or 181 and the key 124 are released, which will render the adjusted stop 45 locked to the carriage and unlocked from the frame.

In view of the rapidity with which the carriage moves step-wise under control of the keys 180, 181, the bringing of either margin stop against the counterstop 46 may be advantageously combined with the movement of the carriage required for outwardly adjusting the margin stop. To accomplish this the stop unlocking key 124 and the appropriate stepping key 180 or 181 may be operated concomitantly. The margin stop which in such case is initially still locked to the carriage will then first move bodily with the carriage into position against the counterstop, and in an automatic manner the unlocking member 122 will then descend to effect a transfer of control of the affected stop from the carriage to the frame, and in a continuing manner the shifting of the stop to the wanted position will be accomplished, the operator releasing the stepping key at the appropriate time concomitantly with or followed by a release of the key 124.

It will be noted that the operator's actions for adjusting either of the stops 44 or 45 are confined to the lightly operative manipulative means comprising the several stated keys in the keyboard 39. Also, that the procedure involves the same steps for adjustment of either margin stop, except that the proper key 71 or 72 must be operated to bring the appropriate stop 44 or 45 first against the counterstop. The operator's hands never need move from the keyboard 39 and the adjustment is effected rapidly with almost no effort on the part of the operator.

If a margin stop needs to be shifted only a single space, the appropriate key 180 or 181 is simply tripped once or twice. If the required adjustment is of considerable extent, one may hold the key 180 or 181 depressed until the approximate point approaches where the stop is desired to be located and the accurate point of adjustment may then be obtained by momentarily depressing the key 180 or 181 once or twice more.

In most instances a margin stop adjustment is best effected by depressing in the procedure the stop unlocking key 124 after the operation of the tabulator key 71 or after the operation of the carriage return key 72. However, one may advantageously adjust the left margin stop 44 inwardly to a position defined or predetermined by a set tabulator stop 77. A carriage return key 72 is first operated to bring the margin stop 44 into engagement with the counterstop. Thereupon, by operation of the stop unlocking key 124, followed by operation of the tabulator key 71, the adjustment of the stop 44 is speedily effected by tabulating travel of the carriage, the said two keys 71 and 124 thereupon released to render the adjustment fixed.

The left margin stop 44 may be adjusted in a quick run to the extreme line-start position from any position short thereof, by mere operation of the stop unlocking key 124 and the carriage return key 72. If these keys 72 and 124 are operated conjointly, or substantially conjointly, the

stop 44 will first move unitarily with the carriage against the counterstop. Then the stop unlocking element 122 will descend automatically under power of the key-tensioned spring 151, and a transfer of control of the stop 44 from the carriage to the frame ensues with the counterstop 46 remaining standing off the rightward end of the perforation 61, and the clutch remaining closed. The carriage return run, meanwhile continues until terminated by the abutment 173 on the left carriage end 19, contacting and displacing the counterstop 46 rightwardly. When thereafter the operated keys are released, the stop 44 will have been secured in extreme line-start position.

It will be noted from the preceding two paragraphs that the margin stop 44 is quickly shiftable under keyboard control in fast, uninterrupted runs, between two predetermined margin determining positions.

Damage to the mechanism due to improper use is virtually impossible. For example, should the operator inadvertently operate the carriage return key 72 after a transfer of control of the margin stop 45 to the frame through operation of the key 124, an automatic shut-off of the power carriage return will nevertheless ensue. Consequential to a power return operation instituted as above noted, when the stop 44 approaches the stop unlocking element 122, the rightwardly extending screw 171 on the stop 44 engages the screw 171 which faces toward it from the stop 45, and forces the latter rightwardly under carriage return power. This cams the slide member 165 on the stop 45 upwardly, inasmuch as such slide member 165 has a cam face 270 for gliding out of the beveled side of the recess 176. In being cammed upwardly, the slide 165 lifts the stop unlocking element 122 by contact with its shelf 123. A path is thus opened for the stop 44 with its parts 52, 165 to ride between said shelf 123 and the housing top plate 62. As the slide 165 on the stop 44 moves over the notch 177 it will move thereinto and stop 44 will consequently become unlocked from the carriage. Return movement continues thereafter until a projecting abutment 273 on the left carriage end, see Figure 1, displaces the counterstop 46 rightwardly to shut-off position. The inadvertently instituted return is thus automatically terminated without its having caused any harm. The slide member 165 of the stop 44 has a short bevel 271, so that in its rightward movement it may not catch on the shelf 123. Upon termination of the stated inadvertent carriage return operation the desired margin stop setting operation may then still be effected in the intended manner.

In a somewhat similar manner, a tie-up is guarded against also when the operator inadvertently operates the tabulator key 71 after having first effected a transfer of control of the stop 44 from the carriage to the frame by the operation of the key 124. Without the feature which is here to be brought out, an institution of a tabulation as stated, under absence of a tabulator stop 77 in encountering relation with the reed 76, would result in tabulating travel of the carriage, stopped short by the right margin stop 45 encountering the left margin stop 44. This would leave the tabulator reed 76 in projected position. Moreover, no restoration of the reed 76 could be effected by any carriage movement, and the escapement releasing arm 82, operated in response to the operation of the tabulator key would re-

main operated, leaving the machine tied up against further use.

According to the invention the margin stop 45, in a tabulation effected under the above stated condition, when it nears the element 122, displaces the stop 44 leftwardly away from the counterstop by the abutment of the aforesaid screws 171. This causes upward camming of the slide 165 on the stop 44, such slide having a cam face 276 like the one on the stop 45 for riding out of a beveled side of the notch 177. Clearance will thus be provided by the upward displacement of the shelf 123 for the stop 45 to ride leftwardly and displace the counterstop 46 leftwardly. The pin 87, on the counterstop arm 60, see Figure 1, imparts ultimately a leftward movement to the upper end of the tabulator reed 76 to free its shoulder 85 from the shelf 86 to thereby cause the restoration of the reed 76 with consequent reestablishment of the escapement control. The margin stop 45 becomes released by downward movement of the unlocking member 122 under the tension of the spring 151. If the spring 151 is made strong enough for the slide member 165 of the margin stop 45 to seat itself firmly down in the notch 176 against the resistance of the rightwardly pulling springs 68 and 83 respectively associated with the counterstop and the tabulator reed, the counterstop will receive said leftward movement immediately after the stop reaches it. However the spring 151 may be made weaker and insufficiently strong to force the slide member 165 fully down into the recess, but yet strong enough to release the stop slide on the stop 45, in which case the leftward displacement of the counterstop will ensue only after the margin stop supporting rack has advanced through the stop 45 to the limit provided by the right carriage end 15. In either case the tabulator reed 76 will be withdrawn as the result of the tabulation, and thus is not apt to cause any trouble when a carriage returning operation is successively instituted. Furthermore, the operator may then still effect the intended setting of the stop 44.

Thus the various power agencies employed in the margin stop setting operation will not tie-up or damage the machine in the event they are operated or used improperly.

While the form of mechanism herein shown and described is admirably adapted to fulfill the objects stated, it is to be understood that it is not intended to confine the invention to the forms or embodiments herein described, for the invention is susceptible of embodiment in various forms, all coming within the scope of the claims which follow.

What is claimed is:

1. In a typewriting machine, a frame, a carriage movable linearly in opposite directions on said frame, margin stops for limiting the opposite directional movements of the carriage, means to support said stops for adjustment in parallel with the movement of the carriage, said stops being normally locked in adjusted position and in condition for release, counterstop means for movement-limiting engagement with the margin stops, power-actuated means for moving the carriage in either direction for engagement of either locked margin stop with the counterstop means, other power-actuated means for rapidly moving the carriage in successive increments in either direction after a margin stop has been engaged with the counterstop means, a keyboard, and means having manipulative devices in or near

said keyboard, to initiate the first said power-actuated means to cause engagement with the counterstop means, of the margin stop which is to be adjusted, to unlock the engaged margin stop and render it stationary with respect to the counterstop means, and to effectuate said other power-actuated means for rapid movement of the carriage in the appropriate direction in successive increments until a desired new position of the unlocked margin stop is obtained.

2. The invention set forth in claim 1, said manipulative devices including a key responsive to which the engaged margin stop is unlocked and rendered stationary with respect to the frame, and including also control means to effectuate said other power-actuated means for appropriate directional movement of the carriage.

3. In a typewriting machine, a frame, a paper supporting carriage having a rack, adjustable margin stops normally in position-controlling engagement with the rack, a counterstop on the frame; power-actuated means for moving the carriage in opposite directions to selectively move the margin stops to the counterstop for an adjusting operation, means to transfer the selected stop from control by the rack to control by the frame to permit the carriage to pass by the stop in either direction, other power-actuated means for effecting successive incremental movements of the carriage in either direction while control of the stop is transferred, thereby to obtain the desired position of the transferred stop on the carriage, and means operable at the will of the operator for controlling the operation of all of the said power-actuated means and the stop-transferring means.

4. The invention set forth in claim 3, the last said means including a tabulator key, a carriage-return key, a stop-setting key for effecting said temporary transfer, and directional keys for control of said other power-actuated means to effect the desired incremental movements of the carriage in the required direction.

5. The invention set forth in claim 4, said machine having a keyboard, and all of said keys being in the area of or adjacent to the keyboard.

6. In a typewriter machine having a frame, a carriage movable thereon and provided with a rack, adjustable right and left margin stops in margin controlling engagement with said rack, and counterstop means on the frame; power-actuated means for moving the carriage in opposite directions to selectively move the margin stops to engage the counterstop means in preparation of a margin stop adjusting operation, means for temporarily transferring the selected stop from control by the rack to control by the frame to permit the carriage to pass by the selected stop in either direction, other power-actuated means for effecting movements of the carriage in letter-feed increments in either direction, after the control of the selected stop is transferred, to effect a repositioning of the selected stop on the carriage, a space-key to control said other power-actuated means for movement of the carriage in single letter-feed direction in letter-feed steps, a line-end lock for said other power-actuated means to incapacitate it in regard to effecting letter-feed steps of the carriage under control of said space-key, and means other than said space-key, differentially operable at the will of the operator for controlling said two power-actuated means and the stop-transferring means, and including means for disabling said line-end lock responsive to opera-

tion of the differentially operable means and to control said other power-actuated means to effect power-movements of the carriage in letter-feed direction.

7. The invention set forth in claim 6, said machine having a keyboard, and said differentially operable controlling means including manipulative devices in or adjacent the keyboard by which to differentially operate it.

8. In a typewriting machine, a frame, a carriage oppositely movable lineally in letter-feed and in return directions on the frame, a line-start and a line-end margin stop for limiting the opposite movements of the carriage, means to support said stops for adjustment in parallel with the carriage, said stops normally locked in adjusted positions and in condition for release, counterstop means for movement-limiting coaction with said margin stop, power-actuated means to step the carriage incrementally in letter-feed direction, a line-end lock for said power-actuated means rendered effective under control of the line-end margin stop in approach of the line-end, a key to render said power-actuated means effective to step the carriage a single increment in letter-feed direction except when said line-end lock is active, manipulative means to unlock any margin stop brought into movement-limiting coaction with said counterstop means, and further to render such margin stop stationary with respect to the counterstop means, and means including manipulative means to render said power-actuated means effective for repeated step movement of the carriage in letter-feed direction, and including means to release the line-end lock for step-movement of the carriage in letter-feed direction.

9. In a typewriting machine, a frame, a carriage movable lineally in letter-feed and in return directions on said frame, a carriage-return and a line-end margin stop, means to support said margin stops for adjustment in parallel with the movement of the carriage, said stops being normally locked in adjusted positions and in condition for release, counterstop means for opposite movement limiting engagement with the margin stops, letter-feed means normally in control of the carriage and operable to cause the carriage to letter feed, a carriage return key, power-means responsive to said key to return the carriage to a position of engagement of the carriage return margin stop with the counterstop means, means including a tabulating key to tabulate the carriage in letter-feed direction to a position of engagement of the line-end margin stop with the counterstop means, means including a key to unlock the engaged margin stop and to render such stop stationary with respect to the counterstop means, power-means to step-move the carriage in carriage return direction, power-means to operate said letter-feed means, a key for each of said last two power means, and means responsive to the operation of each said last two keys to cause its related power-means to function repeatedly during key operation, said various keys being all located in the keyboard or in close adjacency thereto, wherefore adjustment of either margin stop may be speedily effected without lifting the hands from the keyboard.

10. In a typewriting machine, a frame, a carriage movable lineally on said frame, a margin stop, means to support said margin stop for adjustment in parallel with the movement of the carriage, means to lock said margin stop in adjusted position and in condition for release, a

counterstop with which said margin stop assumes an engaged relation in limiting carriage travel in one direction, a device to release the margin stop locking means and concomitantly to lock the margin stop stationary with respect to the counterstop, said device comprising a manual control operable to an operated position independently of the prevalent positional relation of the margin stop with the counterstop, and means controlled by the margin stop to cause the device upon operation of said control to function effectively to release said margin stop locking means and lock the margin stop stationary with respect to the counterstop, either if the margin stop is in engaged relation with the counterstop or consequently to establishment of such relation by a carriage movement.

11. The invention set forth in claim 10, said machine embodying a keyboard, and said manual control being in or adjacent the keyboard.

12. In a typewriting machine, a frame, a carriage movable lineally on said frame, a margin stop, means to support said margin stop for adjustment in parallel with the movement of the carriage, means to lock said margin stop in adjusted position and in condition for release, a counterstop with which said margin stop assumes an engaged relation in limiting carriage travel in one direction, and a device to release the margin stop locking means and concomitantly to lock the margin stop stationary with respect to the counterstop, said device comprising manual control means and means controlled by the margin stop and effective upon operation of the manual control means to cause the device to function effectively and lock the margin stop stationary with respect to the counterstop either if the margin stop is in engaged relation with the counterstop or consequently to establishment of such relation by a carriage movement, said controlled means comprising a flexible element capacitated by the operation of said control means for stop unlocking action but controlled by the margin stop to cause the device to function as stated.

13. In a typewriting machine, a frame, a carriage movable lineally on said frame, margin stops for limiting the opposite directional movements of the carriage, means to support said margin stops for adjustment in parallel with the movement of the carriage, means to lock said margin stops in individually adjusted positions and in condition for release, counterstop means with which the individual margin stops engage in determining opposite writing line margins, and means to release the margin stop locking means for either stop and concomitantly to lock the released margin stop stationary with respect to the counterstop means, said releasing means comprising manual control means operable independently of the prevalent position of the carriage, and means controlled by the margin stops and effective upon operation of said control means to cause the releasing means to function either with respect to a margin stop which is in engaged relation with the counterstop means or with respect to a margin stop which by a carriage movement is moved into engaged relation with the counterstop means while the manual control remains operated.

14. In a typewriting machine, a frame, a carriage movable lineally on said frame, a margin stop, means to support said margin stop for adjustment in parallel with the movement of the carriage, means to lock said margin stop in adjusted position and in condition for release, a

counterstop with which said margin stop assumes an engaged relation in limiting carriage travel in one direction, a device including a remotely located manipulative control, to release the margin stop locking means and to lock the margin stop stationary with respect to the counterstop, comprising, a lock releasing element, and flexibly yieldable means intermediate said manipulative control and the releasing element, and means including margin stop carried means, in control over said releasing element so that when said manipulative control is operated, said releasing element will function and lock said margin stop stationary with respect to the counterstop either if the margin stop is in a relation of engagement with the counterstop or consequently to establishment of such relation.

15. The invention set forth in claim 14, said margin stop carried means which is in control over said releasing element comprising blocking means therefor active unless or until the margin stop is in said relation of engagement with the counterstop.

16. In a typewriting machine, a frame, a carriage movable linearly on said frame, a margin stop, means to support said margin stop for adjustment in parallel with the carriage, means to lock said margin stop releasably in adjusted position, including a releasable lock member carried by the margin stop, a counterstop relatively to which the margin stop is adapted to be brought into an engaged relation for limiting carriage travel in one direction, said counterstop and said margin stop being one on the frame and one on said carriage, a releaser for said lock member, laterally situated stationary with respect to the counterstop, and in operative relation with the lock member only when the margin stop is in the proximity of the counterstop, said releaser operable transversely of the carriage to release said lock member, a primary blocking means including a tappet control on the margin stop, to block the releaser against operation over the whole range of carriage travel except when the margin stop is in the proximity of the counterstop, and a secondary blocking means comprising, a blocking surface located and extending parallel to the carriage for a short distance at the proximity of the counterstop and having an interruption, and comprising further a device on the margin stop which under control of said blocking surface during ineffectiveness of the primary blocking means renders the releaser operable only when the carriage is positioned at or moved substantially to the exact position in which the margin stop is in said relation of engagement with the counterstop.

17. The invention set forth in claim 16, including a manually operable control, and means responsive to operation of said control to urge said releaser to operated position, the releaser moving then to operated position if or as soon as the two blocking means permit it.

18. In a typewriting machine, a frame, a carriage movable linearly on said frame, a margin stop, means to support said margin stop for adjustment in parallel with the carriage, means to lock said margin stop releasably in adjusted position, including a releasable lock member carried by the margin stop, a counterstop relatively to which the margin stop is adapted to be brought into an engaged relation for limiting carriage travel in one direction, an element operable transversely of the carriage for effecting the release of said lock member, laterally

situated stationary with respect to the counterstop, and posed in position for effecting the release of the lock member only when the margin stop is in the proximity of the counterstop, means including a tappet control on the margin stop, to lock said element against effective operation except when the carriage is positioned at or is moved substantially to the exact position in which the margin stop is in said relation of engagement with the counterstop, a control operable to an operated position, and means responsive to operation of said control to operated position to operate said element if or as soon as said locking means permits it.

19. The invention set forth in claim 18, including means to hold the margin stop stationary during the release of the said lock member.

20. The invention set forth in claim 19, said holding means comprising means operable by said element to a holding position.

21. In a typewriting machine, a frame, a carriage movable linearly on said frame, opposite end margin stops, counterstop means with which said margin stops cooperate for limiting the opposite directional movements of the carriage, means to support said margin stops for adjustment in parallel with the movement of the carriage, means for locking the margin stop in different positions of adjustment and in condition for individual release, a margin stop releaser laterally coincident approximately with the counterstop means and operable transversely to the line of carriage travel to release the margin stop locking means and lock said stop stationary with respect to the counterstop means, a manipulative control operable at will, and means for effectively causing the operation of said releaser consequential to operation of said manipulative control only with respect to a margin stop which is in movement limiting relation with the counterstop means, or with respect to a margin stop which by carriage movement is brought into such relation while the manipulative control remains operated, said causing means including means comprising a tappet control on each margin stop to control the releaser for an operation thereof to ensue only after one or the other margin stop is in engaged relation with the counterstop means.

22. The invention set forth in claim 21, including means on each margin stop operable by the releaser to hold the released margin stop stationary in relation with the engaged counterstop means.

23. In a typewriting machine, a frame, a carriage movable linearly on said frame, a margin stop, a counterstop, means to support said margin stop for adjustment on the carriage in parallel with the movement of the carriage, including a releasable latch member on the margin stop, a frame supported releaser for said latch member, operable transversely to the carriage and having a lateral location substantially corresponding to the counterstop, a frame-supported means to block operation of said releaser, tappet means on the margin stop to free the releaser from the blocking means when the margin stop approaches the counterstop, and means to hold the margin stop upon its release stationary with respect to the frame, comprising, an element on the margin stop projectible by operation of said releaser, and surface means on said frame to block said element against projection, said surface means extending parallel to the carriage and having an interruption whereinto said element is holdingly

23

projectible only when the margin stop is engaged with the counterstop, said element when it is blocked, in turn blocking the said margin stop releaser.

24. The invention set forth in claim 23, including, a manipulative control, and resilient means to operate said releaser by said manipulative control.

25. In a typewriting machine having a frame and having a carriage lineally movable on said frame, a left and a right margin stop, counterstop means for contact with said stops for right and left margin establishing action, means to support said stops for adjustment in parallel with the carriage to different margin defining positions, means conditionable to hold either stop in contacting relationship with the counterstop means after establishment of such relationship, said supporting means and said holding means including on each stop normally active latch means and normally released detent means, said latch means constituting part of said stop supporting means and said detent means constituting part of said holding means, means including means operable transversely of the carriage and situated laterally coincident substantially with the counterstop means to engage said detent means and release said latch means of either stop contacting the counterstop means, notch means constituting part of said holding means and engageable by the individual detent means of whichever stop is in contact with the counterstop, surface means at either side of the notch means extending parallel to the carriage, said notch means and detent means including cam faces for the forcing of the detent means of either stop out of the notch means by forced outward movement of either stop which may be contacting the counterstop means, and means to render either stop displaceable outwardly from engaged relation with the counterstop means in the approach of the other stop toward the operable means, this forcing the detent means on the outwardly displaced stop out of the notch means to ride on said surface means, the forcing of the detent means out of the notch means causing a restoration of the operable means to provide clearance for movement of the displacing stop against the counterstop means.

26. In a typewriting machine having a frame a carriage power-movable on the frame in letter-feed and return directions, opposite end margin stops on the carriage and a counterstop means on the frame for limiting the opposite directional movements of the carriage, a keyboard, motor means and power transmission devices on said frame, and manipulative devices in the region of said keyboard for controlling the application of power to various operating mechanisms including a carriage letter-feed, a carriage repeat-letter-feed, a carriage repeat-back-spacer, a carriage tabulator and a carriage-return mechanism; the combination of means for locking the margin stops in adjusted position on the carriage, means controlled by a manipulative device in the keyboard region for operating said locking means to unlock the margin stop from the carriage and lock it to the frame, means including said power transmission devices and under control of certain of said manipulative devices for optionally moving the carriage in either direction to engage either margin stop with the counterstop means, and means including said carriage repeat-letter-feed, carriage repeat-back-spacer, and the said manipulative devices therefor, for power

24

moving the carriage in either direction as desired while the selected stop is held unlocked from the carriage.

27. In a typewriting machine having a frame, a carriage power-movable on the frame in letter-feed and return directions, opposite-end-margin stops on the carriage and a counterstop means on the frame for limiting the opposite directional movements of the carriage, a keyboard, motor means and power transmission devices on said frame, and manipulative devices in the region of said keyboard for controlling the application of power to various operating mechanisms including a carriage letter-feed, a carriage repeat-letter-feed, a carriage repeat-back-spacer, a carriage tabulator and a carriage-return mechanism; the combination of means for locking the margin stops in adjusted positions on the carriage, means controlled by a manipulative device in the keyboard region for operating said locking means to unlock the margin stop from the carriage and to lock it to the frame, means including said power transmission devices and under control of certain of said manipulative devices for optionally moving the carriage in either direction to engage either margin stop with the counterstop means, and means including said carriage repeat-letter-feed, carriage repeat-back-spacer, and the said manipulative devices therefor, for power moving the carriage as desired either in successive repeat movements or in single increments while the selected stop is held unlocked from the carriage, the said manipulative device for operating said locking means being operable either before or after a margin stop is engaged with the counterstop means and the locking of the margin stop to the frame being delayed until the margin stop is engaged with the counterstop means.

28. In a typewriting machine, a frame, a carriage movable lineally in letter-feed and in return directions on said frame, a margin stop, means to support said margin stop for adjustment in parallel with the movement of the carriage, said stop being normally locked in adjusted position and in a condition for release, counterstop means for limiting engagement with said margin stop, letter-feed means normally in control of the carriage and operable to cause the carriage to letter-feed, a carriage-return key, power-means normally responsive to said key to return the carriage, means including a tabulating key to tabulate the carriage, a device to release the margin stop and to lock the same stationary with respect to the counterstop, said device comprising a control key operable to an operated position independently of the prevalent positionable relation of the margin stop with the counterstop, and means controlled by the margin stop to cause the device upon operation of said control to function effectively to release said margin stop and lock the same stationary with respect to the counterstop, either if the carriage stop is in engaged relation with the counterstop or consequently to establishment of such relation by carriage movement in the appropriate direction, power-means to step-move the carriage in carriage return direction, power-means to operate said letter-feed means, a key for each of said last two power-means, and means responsive for the duration of operation of each of said last two keys to cause its related power-means to function repeatedly, said various keys all located in the keyboard or in close adjacency thereto.

29. In a typewriting machine having a letter-feeding carriage, the combination with a line-end margin stop and a counterstop displaceable by said margin stop at line-ends, of typing instrumentalities including type keys, an incremental spacing device for the carriage including a space key, normally idly positioned lock means for said typing instrumentalities and said spacing device, operable to locking position, means to operate said lock means by the displacement of said counterstop at line-ends, and means operable without effect on said counterstop to unlock said spacing device without unlocking the typing instrumentalities.

30. In a typewriting machine having a letter-feeding carriage, the combination with a line-end margin stop and a counterstop displaceable by said margin stop at line-ends, of a normally idle power-spacing device for the carriage, a single action space key and a repeat space key, both normally in control over said power-spacing device, and means operated by the displacement of said counterstop at line-ends to incapacitate said typing instrumentalities and to render said power-spacing device responsive only to the repeat space key.

31. In a typewriting machine, a frame, a carriage movable lineally on said frame, a margin stop, means to support said margin stop for adjustment in parallel with the movement of the carriage, means to lock said margin stop in adjusted position and in condition for release, a

counterstop with which said margin stop assumes an engaged relation in limiting carriage travel in one direction, a device to release the margin stop locking means and to lock the margin stops stationary with respect to the counterstop, said device comprising a manual control, a stop releasing element movable to an operated position for stop releasing action on said margin stop locking means and means to urge said stop releasing element impositively toward operated position responsive to the operation of said manual control, and margin stop controlled means to suppress operation of said stop releasing element by said urging means upon operation of said manual control except if the margin stop is in engaged relation with the counterstop or consequently to establishment of such relation by carriage movement.
